UNITED STATES PATENT OFFICE

HOWARD M. FENSTEMAKER, OF BLOOMSBURG, PENNSYLVANIA

SILK FLYER FOR SPINNING MACHINES

Application filed November 26, 1928. Serial No. 322,059.

This invention relates to spinning machine flyers of that type embodying an anchoring sleeve or journal adapted to be applied to the spindle, a flyer block rotatably mounted upon the anchoring sleeve or journal, and a base plate or spider carrying the flyer wire and mounted upon the flyer block.

The invention has for one of its objects to improve and simplify the general construction of flyers of this character to the end that the work and expense incident to the making and assembling of their parts may be reduced to the minimum, and to attain this end comprehends the provision of a flyer wherein the anchoring sleeve or journal and the flyer block shall be in the form of sleeves each of uniform diameter throughout its entire length and wherein these parts shall be retained in assembled relation by elements 10 terminally carried by one of them, and wherein the base plate or spider shall be retained on the flyer block by said elements.

A further object of the invention is to provide a flyer of the character set forth where 25 in the base plate or spider shall be provided with flyer wire retaining means and a flyer wire locking device so constructed and relatively arranged as to permit a flyer wire of any type to be readily connected to or removed from the flyer.

With the foregoing and other objects in view, the nature which will appear as the description proceeds, the invention consists in the construction, combination and arrangement of parts hereinafter fully described and claimed, and illustrated in the accompanying drawings, wherein:

Figure 1 is a top plan view of the flyer applied to the spindle of a spinning machine;

Figure 2 is a view in side elevation of the flyer and the upper portion of the spindle and bobbin;

Figure 3 is a sectional view taken on a

plane extending vertically and centrally through the flyer;

Figure 4 is a sectional view taken on the horizontal plane indicated by the line 4—4 of Figure 2;

Figure 5 is a sectional view taken on the horizontal plane indicated by the line 5—5 of Figure 2;

Figure 6 is a perspective view of the base plate or spider of the flyer;

Figure 7 is a perspective view of the locking device for the flyer wire;

Figure 8 is a perspective view of the anchoring sleeve or journal of the flyer;

Figure 9 is a perspective view of the flyer block of the flyer;

Figure 10 is a perspective view of a washer forming a part of the flyer;

Figure 11 is a perspective view of the flyer wire shown applied to the flyer in Figures 1 to 5;

Figure 12 is a perspective view of another type of flyer wire;

Figure 13 is a perspective view of another type of flyer wire, and

Figure 14 is a perspective view of a still further type of flyer wire.

Referring in detail to the drawings, 1 designates the spindle and 2 the bobbin of a spinning machine. The flyer which is designated in its entirety by the numeral 3, comprises an anchoring sleeve or journal 4, a flyer block 5 and a base plate or spider 6.

The anchoring sleeve or journal 4 which is mounted upon the spindle 1, is split vertically to permit of its frictional engagement with the spindle. The anchoring sleeve or journal is of uniform diameter throughout its entire length, and is provided at its lower and upper ends with outer flanges 7 and 8, respectively. The flyer block 5 is in the form of a sleeve which is of uniform diameter throughout its entire length and is provided at its lower end with an outer flange 9 and at its upper end with a collar 10. The flyer

block is rotatably maintained on the anchoring sleeve or journal 4 by the flanges 7 and 8 of the latter.

The base plate or spider 6 is rotatably maintained on the flyer block Figures 1 to 5 by the flange 9 and collar 10 of the latter. The base plate or spider which is of elliptical contour, is provided with the central opening 11 for the reception of a flyer block 5, and is provided in its ends with upstanding lugs 12 of segmental formation in plan and arranged with their straight sides innermost. The lugs 12 are provided in their inner sides with horizontal arcuate grooves 13 and with vertical arcuate grooves 14. The grooves 13 are arranged with their bottom walls in the plane of the upper face of the base plate or spider, and the grooves 14 are arranged between the ends of the lugs 12 and concentrically with respect to the opening 11. Each lug 12 is also provided at opposite sides of its groove 14 with slots 15 extending transversely therethrough in parallel relation. The slots 15 of one of the lugs 12 are in alignment with the slots of the other lug, and they communicate with the grooves 13 and 14.

The lugs 12 constitute flyer wire retaining means. The flyer wire may be of any desired or required type. The flyer wire shown in Figures 1 to 5 and 11 comprises arms 16 arranged in axially spaced and parallel relation and provided with downturned outer ends carrying thread engaging eyes 17, a bow 18 extending upwardly from and having a diagonal arrangement with respect to the arms and provided with thread engaging eyes 19, and angular retaining members 20 connecting the ends of the bow and the inner ends of the arms. This wire is adapted to be applied to the base plate or spider 6 in a manner to arrange the inner end portions of its arms 16 in certain of the slots 15 and to arrange its retaining members 20 in the grooves 13 and the remaining slots 14.

The flyer wire shown in Figure 12 comprises parallel arms 21 and 22 and a retaining member 23 which connects them at their inner ends. The arm 21 is provided with a downturned outer end equipped with a thread engaging eye 24, and the arm 22 is provided at its outer end with a thread engaging eye 25 arranged in the plane of the arm 21. This flyer wire is adapted to be applied to a base plate or spider 6 in a manner to arrange the inner end portions of its arms 21 and 22 in the slots 15 of one of the lugs 12 and to arrange its retaining member 23 in the groove 13 of the lug.

The flyer wire shown in Figure 13 comprises a single arm 26 having a downturned outer end provided with a thread engaging eye 27 and provided at its inner end with an angular retaining member 28. This flyer wire is applied to the base plate or spider 6 in a manner to arrange the inner end por-

tion of its arm 26 in one of the slots 15 of one of the lugs 12 and to arrange the retaining member 28 in the groove 13 and other slot of the lug.

The flyer wire shown in Figure 14 comprises a pair of axially aligned and axially spaced arms 29 and 30 and an arcuate retaining member 31 connecting the inner ends of the arms. The arms 20 have a downturned outer end provided with a thread engaging eye 32 and the outer end of the arm 30 is provided with a thread engaging eye 33 arranged in the plane of the arms. This flyer wire is applied to the base plate or spider 6 in a manner to position the inner end portions of the arms 29 and 30 in certain of the slots 15 and to arrange its retaining member 31 between the lugs 12.

The flyer wire with which the base plate or spider 6 is equipped, is positively held in engagement with the lugs 12 by a locking device which comprises a plate 34 and a disc 35. These parts are formed integrally, and are provided with a central opening 36 for the reception of the flyer block 5. The plate 34 is of elliptical contour and rests upon the lugs 12. The disc 35 is arranged between the lugs and rests upon a base plate or spider 6. The external diameter of the disc 35 is less than the distance between the grooves 14, so as to provide spaces 37 between the disc and lugs 12. The locking device is rotatably associated with the base plate or spider 6, and due thereto it may be turned so as to arrange its plate 34 in alignment with or at right angles to the lugs 12. When the locking device is in this latter position the flyer wire may, due to the provision of the spaces 37, be readily engaged with or disengaged from the lugs 12. The locking device is held against accidental, rotary movement by a washer 38 mounted upon the flyer block 5 between the locking device and the collar 10 of the flyer block.

The flange 8 is formed upon the anchoring sleeve or journal 4 after the flyer block 5, the base plate or spider 6, the locking device, the washer 38 and the collar 10 are assembled and placed on the anchoring sleeve or journal, and after the formation of this flange all parts of the flyer are retained in assembled relation against accidental separation.

From the foregoing description, taken in connection with the accompanying drawings, it will be apparent that all parts of the flyer form a self-contained unit, that the parts are simple and capable of being easily and quickly constructed and assembled, and that they may be manufactured at a comparatively low cost.

While I have described the principle of operation of the invention, together with the device which I now consider to be the best embodiment thereof, I desire to have it understood that the device shown is mere-

ly illustrative, and that such changes may be made when desired as are within the scope of the invention and claimed.

What I claim is:

- 5 1. A flyer comprising an anchoring sleeve or journal, a flyer block arranged on the anchoring sleeve or journal, a base plate or spider provided with flyer wire retaining elements and arranged on the flyer block, 70
10 a locking device associated with the base plate and spider and mounted on the flyer block, terminal elements carried by the anchoring sleeve or journal to retain the flyer block thereon, and terminal elements carried 15 by the flyer block for retaining the base plate or spider and locking device thereon.
2. A flyer comprising an anchoring sleeve or journal of uniform diameter throughout its entire length, a flyer block of uniform diameter throughout its entire length and arranged on the anchoring sleeve or journal, a base plate provided with flyer wire retaining elements and arranged on a flyer block, a locking device associated with the 20 retaining elements and arranged on the flyer block, terminal elements carried on the anchoring sleeve or journal for retaining the flyer block thereon, and terminal elements on the flyer block for retaining the base plate 25 or spider and locking device thereon.
3. A flyer including a base plate or spider provided with relatively spaced lugs having horizontal and vertical grooves and vertical slots communicating with the grooves, and 30 a locking device associated with the lugs and adapted to be moved into and out of operative position with respect thereto.
4. A flyer including a base plate or spider of elliptical contour and provided with a 35 central opening, segmental lugs extending upwardly from the base plate or spider at opposite sides of the opening therein, said lugs being provided with horizontal arcuate grooves, vertical arcuate grooves, and slots 40 between which the last grooves are located, and a locking device embodying an elliptical plate and a disc provided with an opening registering with the first opening, the disc resting upon the base plate or spider between 45 the lugs to support said second plate for movement into a position directly over the lugs or into an angular position with respect to the lugs.
5. A flyer including a base plate or spider 50 of elliptical contour and provided with a central opening, segmental lugs extending upwardly from the base plate or spider at opposite sides of the opening therein, said lugs being provided with horizontal arcuate 55 grooves, vertical arcuate grooves, and slots between which the last grooves are located, and a locking device embodying an elliptical plate and a disc provided with an opening 60 registering with the first opening, the disc resting upon the base plate or spider 65
- between the lugs to support said second plate for movement into a position directly over the lugs or into an angular position with respect to the lugs, the diameter of the disc being less than the distance between the vertical grooves so as to provide spaces between the disc and lugs.
- In testimony whereof I affix my signature.
